UNITED STATES PATENT OFFICE.

FRANCIS B. MCKINNEY, OF PITTSBURGH, PENNSYLVANIA, ASSIGNOR TO THE PARELLA CORPORATION, OF PITTSBURGH, PENNSYLVANIA, A CORPORATION OF PENNSYLVANIA.

UMBRELLA.

Application filed April 6, 1928. Serial No. 267,962.

The invention relates to temporary or emergency umbrellas, especially to those adapted to be sold for a small sum, or which are to be used by merchants and other business people for advertising or other purposes.

The objects of the invention are to provide an umbrella of the type referred to which is of simple construction, can be manufactured easily and at low cost from a minimum of inexpensive material, is of self form-sustaining construction and requires no auxiliary handle or other parts used in an ordinary umbrella, and which is highly efficient as an emergency substitute for the usual umbrella.

15 The umbrella according to the invention comprises a sheet of self form-sustaining, sufficiently waterproof, material, provided with a slit extending inwardly from the edge, preferably substantially to the center, the 20 slit edges being overlapped to cause the sheet to assume a conical form, and the overlapped edges then stitched together to maintain the material in its overlapped form. The slit is preferably radial; and the stitching may 25 be done with thread, metal, and the like. Although the structure may be provided with a handle in a variety of ways, this is preferably accomplished by overlapping the slit edges sufficiently to provide an underlying 30 flap of substantial width, and stitching the material close to the edge of the outer, or upper, overlapping portion, whereby the flap referred to forms a gripping member, which may be slotted for hand engagement if desired. The term "self form-sustaining" as 35 used herein refers to material capable of maintaining a shaped form without necessitating any reinforcement.

The invention is illustrated in the accompanying drawings, in which Fig. 1 is a plan view of a sheet of material prepared for constructing an umbrella; Fig. 2 a front elevational view of the sheet shown in Fig. 1 formed into an umbrella; Figs. 3 and 4 are 45 views respectively similar to Figs. 1 and 2 showing a modification; Fig. 5 is a flap-reinforcing member for use with the structure of Figs. 3 and 4; Figs. 6 to 9 are views showing another modification, in which Fig. 6 50 shows a sheet prepared for overlapping; Fig. 7 the completed umbrella; Fig. 8 a flap-reinforcing member; and Fig. 9 a section through

the overlapped portion taken on line IX-IX of Fig. 7.

Referring to Figs. 1 and 2, a sheet 1 of a 55 semi-rigid material possessing sufficient stiffness to make the completed umbrella self form-sustaining, and sufficiently waterproof, such for example, as calendered or parafined cardboard, is provided with a slit 2 60 extending radially from the edge substantially to the center of the sheet, the portions adjacent the slit being indicated by the letters A and B. In order to form the umbrella, portions A and B are overlapped to cause 65 the sheet to assume a conical, umbrella-like form, and the overlapped edges are stitched together, as at 3, Fig. 2, with thread, wire, metal clips, or with any other suitable material. Although the stitching may be done 70 in such a manner as to itself provide a handle, it is preferred to form a gripping member by overlapping the slit edges sufficiently to provide a flap of substantial width on the under side of the umbrella, and to stitch the 75 material near the edge of the overlying, or upper, portion, so that the flap can be seized to support the umbrella over the head. The edge of the flap thus formed is shown in dotted lines at 4, Fig. 2, and the edge of the overlying portion is indicated by the numeral 5.

Although the flap described would in many cases suffice as a gripping member, in the preferred embodiment of the invention gripping is rendered easier and more certain by cutting a slot 6 adapted for engagement by the hand, in the material adjacent one side of the slit and near the edge of the sheet, as shown in Fig. 1. In this case, portion B is lapped 80 over portion A.

A modification is shown in Figs. 3 and 4, in which a sheet of material 7 is provided with a slit 8, which in this case is of curved form, and a slot 9 is cut on one side thereof. The umbrella is shaped, as in the preceding example, by lapping portion C over portion D, and stitching, as at 10, near the overlying edge 11 of portion C. This form of slit provides a flap of greater width at the gripping end.

In order to strengthen the gripping flaps to prevent tearing or destruction thereof, they may be reinforced, and preferably this is accomplished by stitching a strip of the same material to the flap. Fig. 5 shows a re-

inforcing strip 12 adapted for use with the umbrella shown in Fig. 4. This strip is of the same size and outline as the underlying flap-forming portion, and is provided with a slot 9^a which, when the edges of the strip are properly aligned with those of the flap, registers with slot 9. It is disposed against the flap and sewed with it. Such strips may, of course, be used with any of the umbrellas according to the invention.

The sheets used may be of the circular form shown in Figs. 1 and 3, or they may take other forms, for example they may be cut to provide a structure having a notched periphery similar to that of the usual umbrella, as in Fig. 6. Also, the flaps of the umbrellas in accordance with the invention may be formed in other ways.

One such modification is shown in Figs. 6 to 9. An umbrella-forming sheet 15 is blanked from suitable self form-sustaining material to have a continuous series of arcuate notches or scallops 16, of substantially equal size, with the exception of one, 17, which is smaller, the horns of all the notches lying on the periphery of a circumscribing circle, thus providing a sheet of circularly dentate outline. The sheet is provided with a slit 18 extending radially inwardly from one horn of the small notch 17 substantially to the center of the sheet, and a similarly disposed line of weakness 19 extends from the center of notch 17 to a point remote from the periphery, to meet a slit 20 extending laterally from the slit edge toward the line of weakness, as shown in Fig. 6. Slits 21 are cut in the sheet on each side of the line of weakness and adjacent the periphery, in the portion indicated by the letter F. A flap reinforcing strip 22, Fig. 8, is also provided, which consists of a body portion of the same shape as the material between slits 18 and 20 and line of weakness 19, and a head portion having an ear 23 extending laterally from one side. A slot 21^a is also provided in the body portion.

In the assembly of this umbrella, the material between slit 18 and line of weakness 19 is folded on the latter to provide a gripping member, and strip 22 is inserted therebetween, as shown in Fig. 9. The shape of the folded flap produced by lateral slit 20, and of strip 22 permit ready and easy assembly to quickly align the strip with the flap and bring slot 21^a into register with slot 20, it being necessary only to insert the strip between the folds and pull it outwardly until ear 23 engages the material along slit 20 to accomplish this. When the flap has been thus formed, it may be stitched together, or the umbrella may be shaped by lapping portion E over portion F, to produce the conical shape, and then stitched at 24, near the edge of the outer overlapping portion, as shown in Fig. 8. It will be seen that this arcuate notching pro-

duces a truly umbrella-like structure, and the small notch 17 provides for forming the gripping member without interfering with the regular continuity of the notches in the assembled umbrella.

The umbrella according to the invention can be made very inexpensively, the only material required being the sheet material and the thread or other stitching material. The sheets will usually be blanked out from square stock, in which case it will usually be possible to cut the reinforcing strips from the corners. A minimum of operations are necessary, and no supplementary handle, handle-attaching, or rib members are necessary. The umbrellas thus provided are highly efficient for their purpose, and from substantially all standpoints are more satisfactory than the emergency umbrellas heretofore produced.

The umbrellas provided by the invention are especially suitable for advertising purposes, as advertising matter may be printed on either, or both, sides, and owing to their low cost they are suitable for distribution to persons congregated outdoors, as at fairs, athletic events, races, and the like. Or, they may be sold for a small sum, in stores or other places; or by means of dispensing machines situated at convenient points.

According to the provisions of the patent statutes, I have explained the principle and operation of my invention and have illustrated and described what I now consider to be its preferred embodiment. However, I desire to have it understood that, within the scope of the appended claims the invention may be practiced otherwise than as specifically described.

I claim:

1. An emergency umbrella comprising a sheet of self form-sustaining material slit and overlapped to form a conical, umbrella-like structure having an underlying flap of substantial width, and connected together along the upper overlying edge to maintain said form and to leave said flap free for gripping engagement.

2. An emergency umbrella comprising a single sheet of self form-sustaining material of substantially circular outline provided with a slit extending from the edge substantially to the center and overlapped at the slit, the overlapped material being stitched together to provide a gripping flap on the underside and to maintain the material in conical form.

3. An emergency umbrella comprising a sheet of self form-sustaining material provided with a slit extending from the edge substantially to the center and overlapped to form a conical, umbrella-like structure, the underlying flap thus formed being of substantial width, and a stiffening strip disposed against said flap, the material being stitched

together near the edge of the outer overlapping portion, said flap and strip forming a gripping member.

4. An emergency umbrella comprising a single sheet of self form-sustaining material provided with a slit extending from the edge substantially to the center and with spaced slots disposed adjacent one edge of said slit near the periphery, the unslotted portion being lapped over the slotted portion to shape the material into umbrella-like form, the underlying flap thus formed being folded over itself to bring the slots into register, and the overlapped material being stitched together near the edge of the outer overlying portion to maintain said form, said flap providing a gripping member.

5. An emergency umbrella comprising a

sheet of self form-sustaining material of circularly dentate outline provided with a radial slit extending from the edge substantially to the center and overlapped at the slit, the underlying flap thus formed being provided with a radially disposed line of weakness and slit laterally from the edge to said line of weakness at a point remote from the periphery, said flap being folded over itself along said line of weakness; a flap-reinforcing strip disposed within said fold, and a slot through said flap and strip near the periphery, said material being stitched together near the edge of the outer overlapping portion, to form a self-sustaining umbrella structure provided with a gripping member.

In testimony whereof, I sign my name.
FRANCIS B. MCKINNEY.
